(57) **CLAIM**

The ornamental design for a clock, as shown and described.

DESCRIPTION

FIG. 1 is a front perspective view of a clock;
FIG. 2 is a front view of the clock shown in FIG. 1;
FIG. 3 is a rear view of the clock shown in FIG. 1;
FIG. 4 is a right side view of the clock shown in FIG. 1;
FIG. 5 is a left side view of the clock shown in FIG. 1;
FIG. 6 is a top view of the clock shown in FIG. 1; and,
FIG. 7 is a bottom view of the clock shown in FIG. 1.
The broken lines illustrate portions of the clock that form no
part of the claimed design.

1 Claim, 6 Drawing Sheets
